UNITED STATES PATENT OFFICE.

BENJAMIN E. GETCHELL, OF PLAINVILLE, CONNECTICUT, ASSIGNOR TO THE TRUMBULL ELECTRIC MANUFACTURING COMPANY, OF PLAINVILLE, CONNECTICUT, A CORPORATION OF CONNECTICUT.

ELECTRIC RELAY.

Application filed October 25, 1924. Serial No. 745,744.

To all whom it may concern:

Be it known that I, BENJAMIN E. GETCHELL, a citizen of the United States of America, residing at Plainville, county of Hartford, State of Connecticut, have invented a new and useful Electric Relay, of which the following is a specification.

My invention relates to a protecting device particularly for motor circuits intended to automatically open the circuit in case of a dangerous continued overload. The present improvements reside in details of construction facilitating the proper assembly of the parts and assuring permanency and durability, and preventing tampering. In its preferred form the device comprises improvements in the construction of my former applications Nos. 573,965, 624,142, and 669,304.

Figure 1 is a side view of a relay embodying the improvements of my invention.

Figure 2 is a longitudinal sectional view of the same on a larger scale.

Figure 3 is a transverse sectional view on the plane of the line 3—3 of Figure 2, looking in the direction of the arrow.

Figure 4 is a plane figure of one part of the relay body with attached members and omitting the end caps.

Figure 5 is an end view showing the cap in partial section.

Figure 6 is a detailed perspective view of an anchorage member.

In the preferred form the body of the relay is formed of two channel-like insulating members 7 and 8 held together by end caps 9 and 10 which are adapted to fit into terminal clips such as are commonly employed for cartridge fuses. Intermediate between these terminal clips is an auxiliary contact 11 adapted to engage another stationary terminal of the apparatus designed to receive the relay.

Within the channel of the body part 7 is mounted a bimetallic arm 12 adapted to be warped by heat. This member is secured in place by means of a screw bolt 13 and nut 14. The resistance or heater element 15 is also anchored in place by this same screw bolt 13 and has its opposite ends connected to the end caps by means of screws 16 which pass through the end caps and into anchorage blocks 17 so as to securely clamp the end

of the heater strip to the end cap. The anchorage block is shown as tapered at its edges to fit into corresponding recesses in the insulating members 7 and 8 and the ends 18 of the heater strip are bent over the edges of these blocks 17. Preferably the ends 18 are provided with elongated holes 19 so as to facilitate the passage of the screws 16. Each end cap has a boss 20 indented and formed so as to fit into a corresponding recess in the ends of the members 7 and 8 and thus resist rotation of the end cap with respect to the body parts 7 and 8. I also preferably solder the screw 16 in place as shown at 21 so as to prevent the screw from being removed. The angular recess formed in the outer end of the boss 20 assists in anchoring the solder in place and preventing it from being turned with the screw.

Between the heater strip 15 and the base of the thermostatic arm 12 I insert one or more washers 22 having the desired predetermined rate of thermal-conductivity so as to control the time lag of the device and make it certain that a circuit will be opened the desired number of seconds after the predesigned overload has occurred. The contact screw 23 is mounted in an eyelet 24 and adjusted to the proper point for the particular relay. The end of the screw is then covered by a seal 25 preferably of solder which is melted into the end of the eyelet so as to prevent subsequent alteration in the setting of the screw. This eyelet 24 also serves to secure the intermediate terminal 11 to the body part 7. Preferably the heater strip 15 is corrugated or crimped at 26 so as to concentrate its heating effect adjacent the base of the thermostatic strip 12. I also prefer to provide an intermediate shield in the form of an asbestos strip 27 inserted in the channel of the member 7 between the thermostatic arm 12 and the heater strip 15 so as to prevent direct thermal-radiation from the heater strip 15 to the arm 12.

To additionally secure the end caps on the body members I preferably indent them or provide them with interior projections 28 adapted to fit into grooves 29 so as to give additional security against rotation of the end caps. It will thus be seen that when the parts are once assembled and the screws

16 soldered in place, it is practically impossible for the user to take the device apart or tamper with the setting.

I claim:

5 1. An electric relay comprising an insulating body formed of two parts, anchorage members mounted between said parts, a heater strip having its opposite ends bent over said anchorage members, a thermostatic 10 switch having a bimetallic member secured to said heater strip, end caps having introverted portions with non-circular recesses, means for preventing rotation of said caps on said body, and screws connecting said 15 end caps and said heater strip and said anchorage members together, the heads of said screws being soldered against rotation in the recesses in said end caps.

2. An electric relay comprising a two- 20 part insulating body, a heater strip and a thermostatic switch mounted therein, end caps having angular bosses extending into said body providing external recesses, said caps being provided with inwardly projecting lugs engaged in external slots in said body and screws passing through said bosses

and securing them to said heater strip and soldered in said recesses.

3. An electric relay comprising a two-part insulating body having a longitudinal 20 interior passage, a thermostatic switch mounted therein and including a bimetallic arm, a thermal-transmitting member in contact with said arm, a heater strip having a portion in contact with said transmitting 35 member, a screw passing through said heater strip, said transmitting member, and said bimetallic arm and through one part of said body, an external nut for said screw, the head of said screw holding said heater strip, 40 said transmitting member and said bimetallic arm in close contact with each other respectively, anchorage members mounted in said body and having screw seats the ends of said heater strip being bent over outside 45 of said anchorage members and having passes thereto, end caps securing the parts of said body together, and screws extending through said end caps and through the opposite ends of said heater strip and securing 50 them to said anchorage members.

BENJAMIN E. GETCHELL.
